[57] CLAIM

The ornamental design for an epoxy body filler palette,
substantially as shown and described.

DESCRIPTION

FIG. 1 is a top plan view of the epoxy body filler palette
showing my new design;

FIG. 2 is an elevational view taken from the right side
thereof;

FIG. 3 is an elevational view taken from the front side
thereof;

FIG. 4 is an elevational view taken from the rear side
thereof;

FIG. 5 is a bottom plan view thereof; and,

FIG. 6 is an elevational view taken from the left side
thereof.
